UNITED STATES PATENT OFFICE.

ROBERT Z. DRAKE, OF OMAHA, NEBRASKA.

SEASONING PROCESS FOR LUMBER.

Application filed January 2, 1923. Serial No. 610,357.

This invention relates to a process for the treatment of strips of lumber, such as timbers, boards or planks, whereby the moisture contained in green wood may be removed or 5 extracted more quickly than ordinarily, and without forming checks therein or otherwise injuring it, and without impairing its strength. An advantage in the operation of the process is that it tends to cause the desirable, natural color of the timber to be 10 retained, and, if stained or discolored before being treated, it tends to restore the natural color.

It is believed that no natural or artificial 15 process has heretofore been disclosed or used, which, in operation, will attain the above objects.

It is obvious that the natural or open air 20 method is objectionable. While lumber may eventually become seasoned when placed in piles out of doors, the process is slow since sun heat is largely depended upon, and exposure to rain retards seasoning. Also when exposed to continued dry weather, cracks 25 and checks will generally be formed in timbers, planks and boards long before seasoning is effected. Also, on account of exposure to dust, and to rain, and lack of uniformity in 30 drying, the lumber becomes stained and discolored, whereas this process causes it to retain the desirable natural color, if it possesses it before treatment, or to assume that natural color, if not.

It is well known that artificial methods 35 heretofore employed for seasoning lumber, such as timbers, boards or planks, operate to injure them, and often unfit them for commercial use, said methods causing the lumber to dry so quickly at the surface that it 40 soon becomes checked and split, the cracks and checks thereafter being augmented and increased in size when the moisture escapes from the inside. Even comparatively thin pieces, where the shrinkage will be proportionately small, the loss will be quite great; 45 and in instances where planks of two or more inches in thickness are produced from green wood, the damage will be still greater.

By use of the herein described process, 50 timbers, planks or boards newly sawn from green or water-soaked wood, may be quickly seasoned without injury and may be improved by causing them to assume their desired, natural color. To accomplish this, 55 the timbers, boards or planks are conducted to a seasoning house, and are disposed and

supported horizontally, one above the other, with their edges preferably in engagement and arranged in sections as shown in a companion application for Letters Patent filed 60 by this applicant on October 5, 1922, for lumber moving and storage means, Serial 592,459, now Reissue Patent No. 16,361, re-issued June 15, 1926, this arrangement providing vertical, unobstructed passageways, 65 permitting air to move between the sections. In the accompanying drawing, Fig. 1 shows an end view of planks disposed horizontally, in sections, in a seasoning house, the planks of the several sections being supported one 70 above the other with their edges in engagement. Fig. 2 is a plan view, being a section on line 2-2 of Fig. 1. Fig. 3 is a sectional detail showing one of the catches c.

In the drawing, numeral 3 indicates a 75 seasoning house which may have any desired proportion of parts or form, adapted to protect the planks 4 or other lumber-strips or timbers, until they become seasoned, and which will permit a movement of air 80 therethrough.

Any suitable means may be provided for supporting and maintaining the lumber strips 4 in engaging relation, edge-to-edge, to provide vertical sections 5 adjacent to 85 each other, and thereby providing approximately parallel passageways 6 between the several sections, the means herein shown being hanger-bars 7 provided with catches c (shown more fully in my companion application referred to hereinbefore) at their lower 90 ends which engage the lowermost planks of the sections. While I have shown the supporting means c as being in the nature of a resilient catch it is, of course, understood 95 that other forms of means for supporting the lumber between the hanger bars 7 may be utilized without departing from the spirit of my invention. Since cool, dry air has a greater avidity and capacity than warm, 100 moist, ground-surface air for absorbing moisture, means are shown for causing a movement of air from the intake 8 at the top of the seasoning house to be discharged from a power air-fan 9' at the bottom of the 105 house. The structural elements thus described are, for the most part, shown and claimed in the companion patent application above mentioned, and no claim is made 110 for these elements in the present application.

In the practice of the invention, the supported planks 4 may remain in the house

until they become seasoned, and since air may be kept in motion all of the time, the seasoning of the lumber will be practically continuous, this obviously being of advantage to expedite seasoning, as compared with ordinary or natural methods.

Since the hanger-bars 7 are disposed between the sections, the area, in plan, for the air passageways 6 will depend upon the 10 thickness of the hanger-bars, and these bars may have any suitable proportions to control the volume of air which may move through said passageways.

While it has been stated that the planks of 15 each section are disposed in a horizontal position, this particular position is not important provided the planks of a section lie one upon another in a vertical plane with their edges in engagement to form upright, 20 adjacent sections.

Also while it is preferred that the sections 5 shall be disposed vertically, an exact vertical position for the sections is not necessary. This vertical position is desirable for 25 the reason that the source of supply of dry, cool air is generally from higher instead of lower altitudes, although either source may be used, and if the passageways are vertical, the movement of air may be more direct.

30 It is preferred that the hanger-bars be of a thickness corresponding to the thickness of the lumber adjacent thereto so that the volume of air moving in the passageways may be uniform relative to the volume of 35 the lumber, to attain uniformity of seasoning for all of the various sizes of lumber.

It will be seen that, by use of the herein 40 described process, moisture may be removed from the surface of lumber more or less quickly, at will, and as may be desired, and more quickly than it would be removed if subjected to an artificial or heated air process, the reason for this being that cool, dry air is employed, and therefore the present 45 process is of great advantage for avoiding cracks or checks; and by its use, moisture from the interior parts of the lumber will be removed without checking or splitting. Also the process is of advantage, as compared 50 with the natural process since operation may be continuous instead of intermittent so that seasoning of the lumber may be quicker. The lumber will be restored to its natural color, if already discolored, and it 55 is obvious that staining or discoloring may be avoided. One reason why the objects first mentioned may be accomplished by use of the invention is because passageways are employed, the upright walls of which consist of two opposed sides of the exposed 60 planks, another reason being that cool, dry air moves in the passageways.

It will be noted that the hanger-bars are so spaced between the two adjacent tiers or 65 sections of lumber that they tend to prevent

a movement of air lengthwise of the planks, this feature being of advantage to facilitate uniformity in the seasoning.

While it has been stated that the timbers, planks or boards to be seasoned by the present process may be disposed with their longitudinal edges in engagement, this is a feature of convenience only and is not necessary, and the planks of a section may be so disposed that their longitudinal edges will 75 lie near to, but separated from each other, if desired. However, each timber, plank or board of a section should be disposed with its opposed, longitudinal edges in, approximately, a vertical plane.

80 I claim as my invention,—

1. A process for seasoning lumber such as timbers, planks or boards, which consists in supporting them one above another in a seasoning house with their longitudinal edges 85 in engagement in approximately vertical sections adjacent to each other to provide passageways of approximately uniform areas between said sections, subjecting the lumber in said sections to the action of air coming 90 from and having substantially the degrees of temperature of the outside atmosphere, substantially the entire area of said passageways at their uppermost and lowermost parts being in open communication with the air in 95 the seasoning house, the circulating air seasoning the lumber under substantially out of doors conditions without the damaging effects of the hot sun, rain, or the like, and without cracking and discoloring the lumber. 100

2. A process for seasoning lumber, such as timbers, planks or boards, which consists in supporting them one above another in a seasoning house with their respective sides approximately in vertical alignment to provide sections adjacent to each other with passageways of approximately uniform areas therebetween, subjecting the lumber in said sections to the action of air coming from and having substantially the degrees of temperature of the outside atmosphere, substantially the entire areas of said passageways at their uppermost and lowermost parts being in open communication with the air in the seasoning house, the circulating air seasoning the lumber under substantially out of doors conditions without the damaging effects of the hot sun, rain, or the like, and without cracking and discoloring the lumber. 110

115 3. The method of seasoning lumber which consists in supporting the pieces of lumber one above another in a seasoning house with their respective sides approximately in vertical alignment to provide spaced apart sections with substantially vertically extending 120 passageways therebetween, causing outside atmospheric air at substantially atmospheric temperature to enter the seasoning house, positively forcing said air to move through 125 said passageways to contact with the exposed 130

faces of the lumber and gently extract moisture therefrom without cracking or discoloring the lumber being seasoned, the passageways being in open communication at both 5 ends throughout approximately the entire areas of said ends with the air in the seasoning house, and then expelling said air from the seasoning house, the air during its passage through said passageways seasoning

the lumber under substantially out of doors 10 conditions without the damaging effects of exposure to the sun, rain, or the like, to produce seasoned lumber of natural color and substantially free from cracks, warpage and exterior shrinkage. 15

In testimony whereof, I have affixed my signature.

ROBERT Z. DRAKE.
